CLAIM

We claim the ornamental design for a fluid container, as shown and described.

DESCRIPTION

FIG. 1 is a bottom, front, and left side perspective view of a fluid container showing our new design;
 FIG. 2 is a front elevation view thereof (the rear elevation view being identical to the front);
 FIG. 3 is a right side elevation view thereof;
 FIG. 4 is a top view thereof; and,
 FIG. 5 is a bottom plan view thereof.
 Broken line material of FIGS. 1 and 5 is for illustrative purposes only and forms no part of the claimed design.
